Term of patent 14 years

Int. Cl. D12—11

U.S. Cl. D12—118

FIG. 1 is a front elevational view of a set of bicycle fork tips showing my design.

FIG. 2 is a side elevational view of the right fork tip, it being understood that the broken lines are for illustrative purposes only.

FIG. 3 is a side elevational view of the opposite side of the right fork tip.

FIG. 4 is a rear elevational view of the right fork tip taken on the line 4—4 of FIG. 3.

FIG. 5 is a top plan view of the right fork tip taken on the line 5—5 of FIG. 3.

FIG. 6 is a bottom plan view of the right fork tip taken on the line 6—6 of FIG. 3.

FIG. 7 is a side elevational view of the left fork tip, it being understood that the opposite side is a mirror image thereof.

The rear, top and bottom of the left fork tip are identical to the right fork tip shown in FIGS. 4, 5, and 6 except that the gear change hanger arm is omitted from the left fork tip.

I claim:

The ornamental design for a set of bicycle fork tips, as shown and described.
